CONTRA-ANGLE DENTAL HANDPIECE

Harold H. Beardsley, Denver, Colo.

Application April 27, 1937, Serial No. 139,132

9 Claims. (Cl. 32—27)

This invention relates to improvement in dental contra-angle hand pieces and particularly to improvement in burr-receiving, retaining and releasing means in such hand pieces.

Objects of this invention are to provide, in such a device, (a) an improved chuck, (b) improved means for retaining the burr shank in exact axial alignment and eliminating vibration during rotation, (c) improved means for opening the chuck for removal of the burr shank or for admission of the burr shank thereto and for clamping the burr shank in operative position, and (d) providing a rotating clamping means having a smooth exterior.

With these and other objects in view, as will hereinafter more fully appear, my invention comprises certain novel constructions, combinations and arrangements of parts as described in the following specification and defined in the appended claims and illustrated in the accompanying drawings in which:

Fig. 1 is a side elevation of a complete contra-angle hand piece constructed according to my invention.

Fig. 2 is an enlarged fragment of Fig. 1 partly in elevation but mostly in central section illustrating the contracting sleeve in clamping position.

Fig. 3 is a sectional view on line 3—3 of Fig. 2 looking in the direction of the arrows but not including the burr and showing the contracting sleeve in released position.

Fig. 4 is an elevation showing detail of the chuck in Figs. 2 and 3, for tapered burr shank.

Fig. 5 is a section on line 5—5 of Fig. 4 looking in the direction of the arrows.

Fig. 6 is a detail view of a burr with parallel sided shank.

Fig. 7 is a longitudinal section of a modified form of the chuck to accommodate a burr of the type illustrated in Fig. 6.

Figs. 8 and 9 are detail sectional views illustrating structural modifications of the resilient fingers and associated parts. All views are on a greatly enlarged scale.

In the preferred embodiment of my invention as illustrated in the drawings and as herein described, I use any handle and operating parts enclosed therein as now in common use, such handle, including the enclosed parts, being generally indicated at H. Such a handle carries a tubular member 1 which, in turn, carries head housing 2, here illustrated as integral with the tubular member 1. Within member 1 is the usual operating shaft 3 carrying suitable gear 4

which meshes with gear 5 carried by hub 6 having shoulder 7 which bears on a suitable bearing within housing 2 such as the inner end of sleeve 8 threaded into housing 2 and provided with a head 9 for operation thereof and for 5 limiting its movement into the housing.

Hub 6 carries an axially positioned chuck 10 having an axial bore 11 for accommodation of the shank of a burr. The bore 11 and shank 12 of the burr are co-mating and may be tapered 10 as illustrated in Figs. 2 and 3. The chuck 10 is reduced as at 10a and terminates in a frustoconical bearing 10b and is provided with a collar 10c.

The lower or outer end of the chuck 10 is 15 slit as at 13 to form spring fingers 14 and these fingers are preferably provided with projections 15 for engaging shoulder 16 on burr shank 12 when inserted in the chuck and the fingers sprung inwardly as illustrated at Fig. 3. 20

My shank clamping means, hereinafter described when constructed with exact fitting, will hold the shank so tightly within the chuck that rotation of the shank with the chuck will be insured but to insure such rotation even in case 25 of inaccurate construction, positive means to secure such rotation may be provided as flat faced extension 17 of the shank and stop 18 on the inner wall of bore 11 so positioned that it will be encountered by extension 17 in case of 30 any rotative slip of shank 12 in bore 11.

It will be understood that shank 12 is to be inserted in bore 11 until it fits snugly therein and projections 15 are so positioned as to engage shoulder 16 when shank 12 is thus seated and 35 fingers 14 have been contracted. Accordingly tapered shank 12 will be snugly seated in tapered bore 11 and will be positively held against longitudinal movement outwardly from the chuck when fingers 14 are contracted as illustrated in 40 Fig. 2. Normally the fingers 14 flare outwardly to a degree which permits the insertion and withdrawal of burr shank 12 without obstruction by projections 15 so that in order to clamp the shank within the chuck as illustrated in 45 Figure 2, means must be provided for pressing the fingers 14 inwardly after the shank has been inserted in the chuck. Such means must also be capable of releasing such pressure, allowing fingers 14 to resume their normal position when 50 it is desired to withdraw the shank from the chuck.

For this purpose I provide a slidable contracting sleeve or ring 19 slidably enclosing the lower end of chuck 10 and provided at its lower end 55

with a bore 20 having such diameter that when the sleeve 19 is forced over fingers 14 in the position shown in Fig. 2, the fingers will be so contracted that they will bend slightly over shoulder 16 and tightly and firmly, but resiliently, grip said shoulder and thus hold shank 12 in bore 11. Projections 15, are however, preferably provided to make such retention more positive while maintaining resilience which serves a useful purpose in minimizing danger of loosening of parts due to vibration.

Suitable means as bevelled shoulder 21, are provided for contracting fingers 14 and guiding the ends thereof into bore 20 when sleeve 19 is forced up over the chuck 10 from position shown in Fig. 3 to that shown in Fig. 2.

For moving sleeve 19 into or out of the clamping position shown in Fig. 2 I provide a lever preferably of bell crank U form as indicated at 20 22, the lever being fulcrumed at 23 in lug 24 here shown as carried by member 1 and housing 2. The ends 25 of lever 22 engage sleeve 19 in any suitable manner for permitting rotation of sleeve 19 while insuring longitudinal movement 25 of the sleeve 19 with ends 25 of the lever when the lever is moved between the solid line position shown in Figs. 1 and 2 and the position indicated by dotted lines in Fig. 2 and shown in solid lines in Fig. 3. Such means may consist of annular groove 26 in sleeve 19 to accommodate ends 30 25 of the lever 22 which ends are, for this purpose, preferably rounded as clearly shown at Fig. 1.

Bearing member 27 is threaded into housing 35 2, the frusto-conical bearing 10b being seated therein.

Normally ends 25 of the lever will retain sleeve 19 even when in unclamped position as shown at Fig. 3 so that inadvertent dropping of sleeve 19 is provided against and sleeve 19 is normally automatically retained in position for insertion and clamping of the shank and loss of the clamping members is prevented. Two objections to a threaded clamping member, viz: the danger of misplacement or dropping of the member and the knurled or roughened surface provided on such member for turning the same, are therefore obviated by my invention.

Furthermore the operation of my clamping and releasing structure is simplified and facilitated, such operation being accomplished by the thumb or finger of the hand of the operator while holding the handpiece in usual manner.

For burrs having parallel sided shanks as shown in Fig. 6, I provide a chuck of form shown in Fig. 7 which is the same in principle of construction and operation as the chuck shown in the other figures, having the same slot 13 and spring fingers 14, with preferable projections 15. In this modified structure, however, I provide bevelled shoulder 28 on the shank and bevelled seat 29 in the bore of the chuck and recess 30 for reception of flat faced extension 31 to insure rotation of the burr with the chuck.

In Figs. 8 and 9 I have illustrated modifications of structural details of my means for exerting a resilient grip on a burr shank having parallel sides. With such a shank, accurately seated in the chuck, it will be found unnecessary to have the spring fingers contracted forward of the shoulder of the shank, a resilient grip on the parallel sides of the shank being sufficient. In such case the spring fingers 14 may be formed with outwardly projecting portions such as 32 in Fig. 8 or 33 in Fig. 9. In

such case also the sleeve 19 is structurally modified so that when it is forced over the fingers 14 it will contract the projections 32 or 33, as the case may be, thus forcing those portions of the fingers which are adjacent the sides of the shank 5 to grip the shank in a resilient grip thus minimizing the danger of loosening of parts due to vibration.

The smallness of dental hand pieces and the parts thereof and the corresponding minuteness 10 of some of the elements should be kept in mind for clear understanding of this specification and the accompanying illustrative drawings. For example, projections 15 will perform their functions if only $\frac{1}{1000}$ or even $\frac{1}{1000}$ of an inch in depth. 15 Other dimensions may be correspondingly minute.

While I have illustrated and described many details of construction I do not wish to be restricted thereto because many changes in such 20 details, within the spirit of my invention and the scope of the appended claims, will be obvious to those skilled in the art.

I claim:

1. In a dental handpiece, in combination, a 25 housing, a chuck rotatably mounted in the housing and adapted to receive a burr shank having a shoulder, the shank-receiving end of the chuck being divided into a plurality of resilient members extending from said end of said chuck inwardly beyond said shoulder when the shank is seated in the chuck and means slidable over the ends of said members adapted to contract said members and cause said members to resiliently grip said shoulder and a bifurcated bell-crank 35 lever fulcrumed on said housing with its weight arms engaging said slidable means for moving said slidable means into and out of contracting engagement with said resilient members.

2. In a dental handpiece, in combination, a 40 housing, a chuck rotatably mounted in the housing and adapted to receive a burr shank having a shoulder, the shank-receiving end of the chuck being divided into a plurality of resilient members extending from said end of said chuck inwardly beyond said shoulder when the shank is seated in the chuck and means slidable over the ends of said members adapted to contract said members and cause said members to resiliently grip said shoulder and a bifurcated bell-crank 45 lever fulcrumed on said housing with its weight arms engaging said slidable means for moving said slidable means into and out of contracting engagement with said resilient members but adapted to permit rotation of said slidable means 55 with said chuck.

3. In a dental handpiece, in combination, a housing, a chuck rotatably mounted in the housing and adapted to receive a burr shank having a shoulder, the shank-receiving end of the chuck being divided into a plurality of resilient members extending from said end of said chuck inwardly beyond said shoulder when the shank is seated in the chuck, projections on the inner faces of said resilient members and means, operable by a bifurcated bell-crank lever fulcrumed on the housing, slidable over the ends of said resilient members adapted to contract said members and bring said projections into engagement with said shoulder.

4. In a dental handpiece, in combination, a housing, a chuck rotatably mounted in the housing and adapted to receive a burr shank having a shoulder, the shank-receiving end of the chuck being divided into a plurality of resilient mem- 75

bers extending from said end of said chuck inwardly beyond said shoulder when the shank is seated in the chuck and means slidable over the ends of said members adapted to contract said members and a lever whose weight arm engages said slidable means and which is fulcrumed on said housing and adapted to move said slidable means into and out of contracting engagement with said resilient members.

5. In a dental handpiece, in combination, a housing, a chuck rotatably mounted in the housing and adapted to receive a burr shank, the shank-receiving end of said chuck being divided into plurality of resilient members having longitudinally non-rectilinear internal surfaces and means slidable over said members and adapted to contract said members to resiliently grip said shank, and a bifurcated bell-crank lever fulcrumed on the housing and engaging said slid-
10 able means for moving said slidable means into and out of said gripping position.

6. In a dental handpiece, in combination, a housing, a chuck rotatably mounted in the housing and adapted to receive a burr shank, the shank-receiving end of said chuck being divided into a plurality of resilient members and means slidable over said members and adapted to contract said members to resiliently grip said shank and a lever whose weight arm engages said slid-
15 able means and which is fulcrumed on said housing and adapted to move said slidable member longitudinally of the chuck but to permit rotation of said slidable member with the chuck.

7. In a dental handpiece, in combination, a housing, a chuck rotatably mounted in the housing, means slidable over the shank-receiving end of said chuck, resilient means operable by said slidable means for gripping said shank when seated in the chuck and lever means fulcrumed on the housing and whose weight arm engages and is adapted to longitudinally reciprocate said slidable means.

8. In a dental handpiece, in combination, a housing, a chuck rotatably mounted in the housing, means slidable over the shank-receiving end of said chuck, resilient means operable by said slidable means for gripping said shank when seated in the chuck and lever means fulcrumed on the housing and whose weight arm has a peripherally slidable engagement with and is adapted to reciprocate said slidable means longitudinally while permitting rotation of said slidable means with the chuck.

9. In a dental handpiece having a housing, a burr shank chuck rotatably mounted in the housing and clamping means moveable longitudinally of the chuck for clamping and unclamping the shank, a bifurcated bell-crank lever fulcrumed on the housing having weight arms engaging the clamping means to move the said means longitudinally and permit the rotation of said means with the chuck when clamped thereon.

HAROLD H. BEARDSLEY.
